UNITED STATES PATENT OFFICE

HARRY C. FOSTER, OF CONNERSVILLE, INDIANA, ASSIGNOR TO INDIANA LAMP CORPORATION, OF CONNERSVILLE, INDIANA, A CORPORATION

MULTIPLE SIGNAL LIGHT AND UNIT ASSEMBLY

Application filed May 7, 1927. Serial No. 189,539.

This invention relates to a combination stop and tail light.

The chief object of the invention is to provide a unit assembly consisting of but a minimum number of parts and these so arranged as to be readily assembled and secured in assembled relation with minimum difficulty.

One feature of the invention consists in the provision of an insulated support readily receivable by a combination stop and tail light casing and adapted to convey energy to a pair of light bulbs, one mounted in a stop light compartment for stop light purposes and the other mounted in a tail light compartment for tail light purposes and the formation of the compartments by a partition bracket which in addition to forming the compartments serves as a support and retainer for the respective light bulbs mounted in the compartments and also serves as a support for the combination light closure and the insulated support when desired.

The full nature of the invention will be understood from the accompanying drawings and the following description and claims:

In the drawings Fig. 1 is a front elevational view of the invention. Fig. 2 is a similar view with the cover and light bulbs removed. Fig. 3 is a central sectional view taken on line 3-3 of Fig. 2 and in the direction of the arrows. Fig. 4 is a perspective view of the saddle and terminal support in detached relation.

In the drawings 10 indicates a casing forming the shell of a combination stop and tail light. The casing has the aperture 11 for directing rays downwardly upon a license plate by the tail light 12. The lens or closure 13 is mounted by means of the rim 14 on the casing and completely closes the same, said rim including a transverse portion 14^a that is anchored at 15 to a partition 16 forming two compartments 17 and 18, 17 containing light bulb 12 and 18 containing light bulb 19 and reflector 9. The partition in turn includes a pair of angularly extending ears 20 by which the partition is secured to the casing 10 and which are similar to ears 15.

The casing 10 includes the apertures 21 countersunk at 22 to receive threaded bolts 23

rigidly anchored therein by the washer or retainer ring 24. Studs 23 serve as supports for the light. An extension 25 of the partition is depressed at 26, forming a socket which over-lies the stud 23 in chamber 18, and is apertured at 7 to receive the reflector anchorage 8. The extension 25 serves as an aligning member since when the recess 26 is seated over stud 23, the apertures 27 in the partition ears 20 register with apertures formed in the casing 10 so that the partition may be readily secured in predetermined relation. Each aperture 27 is threaded to receive a bolt presented from outside the casing. Thus the entire light may be assembled as units and then united externally.

The casing supports a tubular socket 30 which is provided with J-slots for contact plug reception and slidably mounted therein is the multiple circuit plug formed of a cylindrical insulation body portion 32 with a circular flange or face 33 milled or flattened at 34 for abutment adjacent the partition 16 when in assembled relation. The partition thus serves as an aligner for positioning the support 32 in predetermined relation relative to the slots 31. In a groove 35 transverse to the flat face 34 and in the front face of the circular flange 33 is mounted a pair of spring contacts 37 and 38, the former extending longitudinally from the flange 33 and substantially parallel to the partition 16. The latter extends angularly and at approximately 45 degrees to the longitudinal extension and the flange portion 33. Screws 39 position the spring contacts upon the insulation body and extend rearwardly and have threaded connection with the tubular current conducting members 40 each of which slidably supports a contact member in inverted relation similar to the member 40 and indicated by the numeral 41. The two telescopically associated members 40 and 41 form a chamber 42 in which is mounted a spring 43 for normally maintaining contact member 41 in the projected position for contacting terminal contact carried by the plug receivable by the socket portion 40. The spring contacts 37 and 38 and the insulation body are a separate unit readily receivable by the tubular socket 30.

The partition 16 is apertured at 50 to receive the light bulb 19 and projecting into chamber 18 are the arcuate lips 51 constituting an aligning support for the light bulb. Extending oppositely therefrom and arranged in spaced relation and at 90 degrees thereto are the angular bulb guiding extensions 52 which adjacent the anchorage thereof to the partition at 53 are relieved to permit the passage of the pins carried by the light bulb. The inwardly directed angular ends of extension 52 limit axial bulb seating movement. The light bulb is thereupon rotated ninety degrees to seat said pins in recesses 54 formed at the junction of the arcuate aligning lips with the partition.

The partition 16 rigidly supports a saddle having the anchoring outwardly directed flanges 60 anchored as at 61 and the parallel side walls 62 connected by an inclined straddling portion 63 provided with an opening 70 having the lips 71 at opposite sides thereof and directed outwardly and oppositely from the lips 51. The oppositely extending bulb guiding angular members are indicated by the numeral 72 and terminate in bulb travel limiting inwardly directed ends and the relieved portions for pin passage adjacent thereto are indicated by the numeral 73 and the pin receiving seats are indicated by the numeral 74, the same being similar to the identical construction formed in the partition itself. The result is a light bulb support at 45 degrees for the light bulb 12. As shown 35 the light bulb 19 engages contact 37 and light bulb 12 engages contact 38 and thus the circuit is completed to each. The bulb guiding extensions maintain predetermined positioning of the bulb when mounted.

As a further means of positioning parts in predetermined relation, and if desired the same may be utilized for maintaining the terminal support 32 upon the partition 16 prior to final assembly, and for such purpose the insulation flange 33 includes the recess 66 at each side and extending into the same from each side wall 62 of the saddle is a clamping tongue 67, see Fig. 4, which shows the same in detached relation. Preferably 45 reflector 9 is secured to the partition prior to the anchorage of the latter to the casing.

The resultant construction permits the partition to support the insulation body 32 with the current conducting connection and serves 55 as a support therefor in positioning the same in the tubular socket 30. Positioning of the aforesaid in the tubular socket 30 serves, when the body 32 is seated, to align the partition with the body openings when the tongue 25 60 with the socket 26 is in registration with the stud 23.

The invention claimed is:

1. In a light construction, including a casing, and a partition forming two compartments therein, the combination of an insula-

tion plug, a pair of terminal conducting contacts insulatably supported thereby, a pair of angularly arranged bulb receiving sockets supported adjacent thereto and in angular relation to said contacts, one socket being transverse to the plug axis, said sockets positioning a bulb in each compartment, and a pair of terminal spring contacts connected to said first-mentioned contacts, one of the second-mentioned contacts being L-shaped with one arm projecting outwardly in longitudinal alignment with the insulation plug and the other contact being V-shaped and extending angularly thereof and of the longitudinal contact, the free end of the V-shaped contact extending toward the free end of the L-shaped contact. 70

2. In a combination stop and tail light construction, a casing, a multiple compartment forming transverse plate partition therein 85 extending completely across the same and from front to back, a saddle supported thereby having a portion inclined to the plate and in spaced relation therewith, and a pair of light bulb-receiving anchorages, one provided in said saddle inclined portion and another in the partition adjacent the saddle anchorage. 90

3. A device as defined by claim 2, characterized by the addition of an insulation plug 95 carried by the casing, a pair of terminal conducting contacts insulatably supported thereby, said light bulb-receiving anchorages being arranged in angular relation thereto, one being transverse to the plug axis, a pair of terminal spring contacts connected to said first mentioned contacts, one of the second mentioned contacts being L-shaped and projecting outwardly in longitudinal alignment with the insulation plug and parallel to the partition and the other being V-shaped and extending angularly of the plug and of the longitudinal contact and in parallel relation to the saddle inclined portion, the free end of the V-shaped contact extending toward 100 the free end of the L-shaped contact. 105

4. A device as defined by claim 2, characterized by the addition of an insulation plug carried by the casing, a pair of terminal conducting contacts insulatably supported thereby, said light bulb receiving anchorages being arranged in angular relation thereto, one being transverse to the plug axis, a pair of terminal spring contacts connected to said first mentioned contacts, one of the second mentioned contacts being L-shaped and projecting outwardly in longitudinal alignment with the insulation plug and parallel to the partition and the other being V-shaped and extending angularly of the plug and of the longitudinal contact and in parallel relation to the saddle inclined portion, the free end of the V-shaped contact extending toward the free end of the L-shaped contact, and cooperating portions on the insulation body and 115 120 125 130

partition and on the partition and saddle portion for predetermined positioning of the body, partition and saddle portion and for anchoring the same together.

5 5. A device as defined by claim 2, characterized by the combination light construction including a closure for the casing, and the addition of an insulation plug carried by the casing, a pair of terminal conducting contacts insulatably supported thereby, said light bulb receiving anchorages being arranged in angular relation thereto, one being transverse to the plug axis, a pair of terminal spring contacts connected to said first mentioned 10 contacts, one of the second mentioned contacts being L-shaped and projecting outwardly in longitudinal alignment with the insulation plug and parallel to the partition and the other being V-shaped and extending angularly of the plug and of the longitudinal contact and in parallel relation to the saddle inclined portion, the free end of the V-shaped contact extending toward the free end of the L-shaped contact, an angular extension extending oppositely from the saddle, a reflector, means rigidly connecting said reflector to said extension for unit assembly, co-operating portions on the insulation body, partition and saddle portion for positioning the 15 same in predetermined relation and for anchoring the same together, means uniting the partition to the casing, and other means uniting the closure to the partition for completely uniting the construction together in rigid 20 connection, said partition constituting the sole rigid connection between the closure and the casing.

In witness whereof, I have hereunto affixed
my signature.
